RAIL ANCHOR

Application filed June 24, 1929. Serial No. 373,198.

The present invention relates to rail anchors for preventing rail creepage, and more particularly to anchors of the one-piece type that are adapted to be sprung into firm gripping engagement with the rail base.

One piece rail anchors constructed to be sprung into gripping engagement with a rail base have been proposed heretofore, but in many of these prior devices the construction is such that the spring action relied upon to hold the anchor in firm gripping engagement with the rail exerts continuously upon the rail engaging elements approximately the maximum gripping force, and the structural embodiment employed did not lend itself to an increase in the gripping action transversely of the rail as the load thrust increases. As a result the inevitable metal fatigue of the anchor was accelerated by this high tension and by the varying load thrusts produced by the tendency of the rail to creep, causing the anchor to gradually release its firm grip upon the rail.

In other constructions proposed heretofore no provision is made for yieldingly absorbing load thrusts of exceptional magnitude and as a result the rail anchor either breaks or is forced bodily lengthwise of the rail by the excessive rail creeping forces, and in either case these rigid or non-resilient rail anchors are incapable of springing back to their original position upon the rail to resume their rail holding function.

In still other constructions employed heretofore, overhanging jaws are provided at each end of the rail anchor which are required to be sprung or bent over the edges of the rail base flange to hold the anchor in place, but these anchors are difficult to apply to and remove from the rail and are likely to be subjected to excessive strains during their application or removal from the rail.

The present invention seeks to overcome the above mentioned objections to the rail anchors proposed heretofore, and is directed to a strong durable construction which is simple and inexpensive to manufacture, is easy to apply to and remove from a rail without the use of special tools, is adapted to exert a continuous spring gripping action

upon the rail which prevents possibility of the anchor being accidentally disengaged from the rail, and which will not move relative to the rail when subjected to average or normal creepage load thrust but has an end portion that is capable of increasing the frictional bite and spring energy of the entire rail anchor device by a slight movement lengthwise of the rail under a load thrust of exceptional magnitude and which end, due to its position of angularity in relation to the rail flange embracing jaws on the opposite end, will automatically spring back to its original position when relieved from the exceptional displacing load thrusts.

One of the important features of the present invention resides in a one-piece resilient rail anchor having a shank adapted to extend transversely of the rail in abutting engagement with the under face thereof, and having a plurality of jaws adapted to engage the upper face of the base flange and hold the shank firmly against the under face of the rail. As a result of this construction the spaced overhanging jaws hold the shank so firmly against the under face of the rail that it is unnecessary to provide the shank with overhanging flange-engaging means at its opposite end. This makes the rail anchor easy to apply to and remove from the rail.

Another feature of the invention resides in a laterally extending resilient arm at the opposite end of the shank from that of the overhanging jaws, and which extends from the shank in the direction of the on-coming traffic and abuts firmly against the edge of the rail base flange with a spring action that serves to maintain a constant firm grip upon the rail. This arm is also adapted to resiliently absorb the load thrust of exceptional magnitude and, due to its peculiar construction and position relative to the jaws on the opposite end and the transverse shank member, it will react to spring back to its original position when relieved from this excessive longitudinal load thrust.

Still another feature of the invention resides in a one-piece rail anchor which may be readily formed of sheet metal by shearing and bending operations, and more specific

features of the invention reside in the construction and arrangement of the overhanging jaws provided at one end of the shank for firmly engaging the upper inclined face of the rail base flange.

Other features of the invention and novel combination of parts in addition to the above will be hereinafter described in connection with the accompanying drawings which illustrate good, practical forms of the invention.

In the drawings,

Fig. 1 is a perspective view of a rail anchor constructed in accordance with the present invention and shown as secured to a rail in position to abut against a tie;

Fig. 2 is a vertical sectional view through a portion of the rail base showing the engagement of the overhanging jaws of the rail anchor therewith;

Fig. 3 is a side elevation of a rail anchor blank which has been cut and is ready to be bent into final shape;

Fig. 4 is a perspective view of a rail anchor formed from the blank shown in Fig. 3;

Fig. 5 is a side elevation of the portion of the rail anchor having the overhanging jaws;

Fig. 6 is a top plan view of the rail anchor of Fig. 4;

Fig. 7 is a vertical sectional view through a portion of the rail showing the rail anchor in position to be secured to the rail base;

Fig. 8 is a view similar to Fig. 7, but shows the rail anchor attached to the rail base;

Fig. 9 is a top plan view of Fig. 8, showing the rail anchor in normal abutting engagement with the tie;

Fig. 10 is a view similar to Fig. 9, but shows the right-hand portion of the rail anchor as shifted lengthwise of the rail by the pressure against the tie;

Fig. 11 is a side elevation of a modified type of rail anchor blank;

Fig. 12 shows the rail anchor formed from the blank of Fig. 11;

Fig. 13 is a top plan view of the rail anchor of Fig. 12; and

Fig. 14 is a top plan view of a further modified type of rail anchor.

Referring to the drawings, 10 is the wheel engaging portion of a rail of usual construction, 11 is the rail base flange that is connected to the upper portion 10 of the rail by the centrally disposed upstanding web 12, and the rail base 11 is provided with the usual upper inclined face 13 and with the opposite vertically disposed edges 14.

While the rail anchors disclosed in the drawing may be formed of sheet metal by relatively simple cutting and bending operations, it will be apparent that these rail anchors may also be forced or otherwise constructed.

Referring first to the rail anchor construction shown in Figs. 1 to 10 inclusive, the rail anchor consists of a shank 15 adapted to ex-

tend transversely of the rail, in position to rest firmly against the vertical face of a tie 16 as shown, and this shank is provided with an upper edge 17 which is adapted to rest firmly against the bottom or under face of the rail base. The shank 15 is preferably made relatively wide so that it will extend downwardly a substantial distance from the under face of the rail to provide a tie engaging element of relatively large area.

The rail anchor shank 15 is provided at one end thereof with a plurality of overhanging jaws, three jaws being shown in the embodiment of the invention illustrated in Figs. 1 to 10 inclusive, while two overhanging jaws are shown in the modified construction of Figs. 11, 12 and 13.

The rail anchor construction of Figs. 1 to 10 inclusively is conveniently formed from a sheet metal blank which may have substantially the rectangular configuration of Fig. 3, one entire upper corner of the blank being cut away lengthwise of the blank well towards the central portion thereof, and the edge of the rail anchor 17 adapted to abut against the under face of the rail is formed by providing the central portion of the blank with a relatively long cut extending lengthwise of the blank, as will be apparent from Fig. 3.

This cut extends a substantial distance under the remaining upper portion of the blank, and the upper portion of the blank is further cut away along the angularly disposed lines 18 and 19 to form a clearance space for an edge portion of the rail base flange 11 and to provide the overhanging jaws 20 and 21. The jaw 20, it will be noted, lies directly over the shank 15 and extends inwardly a substantial distance towards the central vertical web 12 of the rail to engage

the upper inclined face 13 of the rail base at a point disposed inwardly a substantial distance from the rail edge 14. The second or auxiliary jaw 21 is formed by bending that portion of the overhanging metal having the inclined surface 19 away from the rail web 12 to form the jaw 21 which is disposed in lateral spaced relation to the jaw 20 and is connected to the latter by the arcuate portion 22.

The third overhanging jaw above mentioned is formed by bending the left-hand end portion of the blank shown in Fig. 3 back upon itself, as will be apparent from Figs. 4 and 6, to provide the inwardly extending end portion of the rail anchor in which the jaw 23 is formed by providing in this end portion the relatively deep notch or recess 24 formed to provide a clearance space for the edge of the rail base flange, and also to provide the jaw face 25, adapted to engage the upper inclined surface of the flange, and the jaw face 26 adapted to engage the lower or under face of the rail base. The jaws above described should be so constructed that they

130

5 may be forced into rigid gripping engagement with the rail base flange, without abutting against the vertical edge 14 of the rail base and the rail anchor is therefore provided with the clearance spaces 27 and 28 adapted to clear the vertical edge 14 of the rail base.

10 As above stated, it is important that the overhanging jaws shall serve to hold the edge 16 of the shank firmly against the under face of the rail base flange 11, and it is therefore desirable that the first-mentioned jaw 20 shall extend inwardly a substantial distance from the rail edge 14 and grip the upper inclined flange of the rail base adjacent its inner end. To insure this the flange engaging face 18 of the jaw 20 is normally disposed at a slight angle to the inclination of the upper surface 13 of the base flange. For 15 example, if the upper face 13 of the base flange is disposed at an angle of say 14° to the under face of the rail, then the face 18 of the jaw 20 should be disposed at an angle of about 11° to the upper edge 17 of the rail 20 anchor shank. This will not only insure the engagement of the jaw 20 with the rail base flange at a point inwardly a substantial distance from the edge of the rail, but will cause this jaw to spring upwardly slightly 25 when subjected to a pronounced gripping action, to accommodate itself to the inclination of the upper surface 13 of the rail base.

25 It is desirable that the flange engaging surface of the overhanging jaws 20, 21 and 23 be staggered slightly with respect to a horizontal plane to subject these jaws to a torsional twist as they are forced into gripping engagement with the rail base flange to thereby increase their gripping action upon this flange. This is accomplished by forming the lower surface 19 of the jaw 21 so that it extends downwardly at a greater angle than the surface 18 of the jaw 20, as will be apparent from Figs. 2 and 5. This causes the outer end 40 portion of the surface 19 of this auxiliary jaw to extend an appreciable distance below the surface 18 so that this jaw, which is obviously more resilient than the jaw 20, may spring upwardly to accommodate itself to the inclination of the upper face of the rail base as the jaws are forced into gripping engagement with the rail base. Likewise the jaw engaging surface 25 of the jaw 23 is preferably disposed slightly below the surface 18 of the 55 jaw 20 to cause this jaw to be subjected to a torsional stress as it is forced into engagement with the rail base flange to increase its gripping action upon such flange.

60 It will be seen from the jaw construction just described that these jaws will engage the rail base flange with a powerful gripping action, and since the three jaws are spaced from each other lengthwise of the rail, this gripping action will be disposed over a relatively 65 large area, all of which will serve to hold

the upper edge 17 of the shank very firmly against the under face of the rail base.

70 The rail anchor is provided at its opposite end with a laterally extending arm 29 which is preferably given the arcuate construction shown, and this arm 29 extends away from the tie 16 in the direction of the on-coming traffic. The outer end 30 of this arm is adapted to abut firmly against the vertical edge 14 of the rail base and the upper face of 75 this arm 29 is therefore formed so that it extends upwardly near its outer end a substantial distance above the upper edge 17 of the shank. This upwardly extending portion of the arm 29 is conveniently formed by 80 providing the blanks shown in Fig. 3 with the inclined upwardly sloping surface 31 which may extend from a shoulder 32 disposed at one end of the shank bearing edge 17 to the outer end of the arm 29, as will be 85 apparent from Fig. 3. The construction of the arm 29 is such that when the shank 15 is forced upwardly against the under face of the rail by the overhanging jaws 20, 21 and 23, the outer end of the arm 29 will tend to 90 spring upwardly into abutting engagement with the rail edge 14 and will move to this position as soon as the rail anchor has been shifted transversely of the rail far enough to cause the upper face of the arm 29 to clear 95 the under face of the rail.

When it is desired to secure the rail anchor of the present invention to a rail, this is readily accomplished by placing the rail anchor by hand in the position in which it is shown 100 in Fig. 7, whereupon the overhanging jaws may be forced into rigid gripping engagement with the rail base flange by striking with a spike maul or the like upon the rounded left-hand end portion 33 of the rail anchor, 105 and at the same time exerting a prying action upon the opposite end of the rail anchor by inserting the small end of a track bar or track wrench in the clearance space provided between the inner face of the arcuate arm 29 and the edge of the rail to thereby cause the outer end of the arm 29 to spring outwardly 110 into abutting engagement with the rail edge as shown in Fig. 1 of the drawing.

115 The shoulder 32 is normally inactive and lies in spaced relation to the edge of the rail base as shown in Figs. 9 and 10, it being intended that this shoulder shall engage the edge of the rail only when the rail anchor is subjected to a retrograde movement which 120 will shift the rail anchor diagonally of the rail to an increased angle from that in which it is shown in Fig. 9. This shoulder 32, while normally inactive when the anchor is secured to the rail, performs an important function in facilitating the removal of the anchor from the rail in that it serves to hold the shank 15 out of engagement with the under face of the rail when the rail anchor is 125 removed. This will be understood by 130

pointing out that the rail anchor may be removed from the rail by striking downwardly in an inclined direction upon the upper surface of the arcuate arm 29 to force the upper face of the shoulder 32 into engagement with the under face of the rail whereupon the outer end 30 of the arm 29 may be moved downwardly entirely out of engagement with the edge 14 by delivering one or more additional blows to the upper face of the arm 29 to force the rail anchor to the position in which it is shown in Fig. 7, whereupon it may be readily removed by hand from the rail.

It will be apparent from the construction so far described that the resiliency of the arm 29 and shank 15 serves to hold the outer end 30 of this arm against the edge of the rail with a strong spring action that prevents any possibility of the rail anchor becoming accidentally disengaged from the rail. In most cases a gripping action of the overhanging jaws upon the rail base flange will be sufficiently rigid to prevent movement of these jaws relatively to the rail when the rail anchor is subjected to a load thrust of exceptional magnitude with the result that when an excessive load thrust is exerted upon the rail anchor the shank will be bent or bowed from the position in which it is shown in Fig. 9 to the position in which it is shown in Fig. 10, whereupon the outer end 30 of the arcuate arm will automatically increase the spring clamping action and gripping forces of the rail anchor on the rail in a ratio substantially equivalent to the increase in the creepage load. When the rail anchor is no longer subjected to this exceptional load thrust the resiliency of the rail anchor will cause the parts to spring back to the normal position in which they are shown in Fig. 9 and this return of the parts to the normal position will be assisted by the vibrations imparted to the rail by the rolling stock.

The auxiliary jaw 21, it should be noted, is offset from the vertical plane of the rail anchor shank away from the on-coming traffic, and lies over the anchor engaged tie. As a result of this arrangement the arm 21 will oppose any tendency of the rail anchor to rock about its upper longitudinal edge 17 under the tie pressure.

In some cases it may be found unnecessary to employ all three of the overhanging jaws shown in Figs. 1 to 10 inclusive in which case the modified construction shown in Figs. 11, 12 and 13 may be employed. This modified construction it will be noted differs from the three-jaw-construction above described only in that the jaw 21 has been omitted and this is readily accomplished by cutting away that portion of the blank shown in Fig. 3 forming the arm 21, as will be apparent from Fig. 11, and it will be seen that the blanks shown in Figs. 3 and 11 may be

identical except that the portion of the blank provided in Fig. 3 to form the auxiliary arm 21 has been cut away in the blank disclosed in Fig. 11. The overhanging jaws 20 and 23, and the arcuate laterally extending arm 29, of the modified construction shown in Figs. 11, 12 and 13, may be formed as above described in connection with Figs. 1 to 10 inclusive and may operate in the manner above set forth.

In Fig. 14 of the drawing a still further modified construction is shown, in which a single overhanging jaw 34 is provided upon the rail anchor, which jaw is offset from the vertical plane of the shank and lies in approximate alignment with the abutting end 35 of the laterally extending arcuate arm 36. In this modified construction of Fig. 14, the offset portion 37 provided with the overhanging jaw 34 is connected to the shank 38 by the inclined web 39, the arrangement being such that the upper edge of the shank 38 and web 39 may abut against the under face of the rail base flange 11, while the jaw 34 extends over this flange in firm gripping engagement with the upper inclined face 13 of the rail base. This modified construction of Fig. 14 may be applied to and removed from the rail in the manner above described, and the end 35 of the arm 36 is maintained in firm abutting engagement with the edge 14 of the rail by the resiliency of the web 39, shank 38, and arcuate arm 36.

It will be seen from the foregoing that each of the rail anchors herein shown and described is comparatively simple and inexpensive to manufacture, and may be easily applied to and removed from a rail, and it will be understood that the grip which the rail anchor exerts upon the rail will increase with the load thrust exerted upon the rail anchor by the creeping rail. It will also be understood that when the rail anchor is relieved from a load thrust of exceptional magnitude, it will spring back to its original position with respect to the rail. The direction of traffic over the rail is indicated by the arrow of Fig. 1.

Where the rail anchor is provided with three jaws at one end, such as illustrated in Figs. 4, 9 and 10, one of the jaws, such as 21, is positioned laterally of the shank over the cooperating tie, while the other jaw 23 is at the side of the shank away from the tie. When it is desired to use only two jaws connected at one end of the shank, the present invention contemplates that the auxiliary jaw 23 which is retained in the two-jaw structure when the jaw 21 is removed as described, shall extend in a vertical plane laterally of the shank away from the cooperating tie.

What is claimed is:

1. A rail anchor consisting of a shank adapted to extend across the rail base and provided at one end with three integral jaws

positioned to extend over the rail base flange a substantial distance and engage the upper inclined face of said flange with sufficient force to hold the shank firmly against the under face of the rail base, and means at the 5 opposite end of the shank for engaging the base flange at the opposite side of the rail.

2. A rail anchor consisting of a shank adapted to extend across the rail base to abut 10 against a tie and provided at one end with three integral laterally spaced jaws positioned to extend over the rail base flange a substantial distance to engage the upper inclined face of said flange with sufficient force 15 to hold the shank firmly against the under face of the rail base, and means at the opposite end of the shank for engaging the base flange at the opposite side of the rail.

3. A rail anchor consisting of a shank 20 adapted to extend across the rail base to abut against a tie and provided at one end with three laterally spaced jaws adapted to extend over the rail base flange and engage the upper inclined face of said flange at a substantial 25 distance from the rail edge to hold the shank firmly against the under face of the rail base, and an arm at the other end of the shank adapted to be sprung into abutment with the rail edge.

30 4. A one-piece rail anchor consisting of a shank adapted to extend across the rail base to abut against a tie and provided at one end with three laterally spaced jaws adapted to extend over the rail base flange a substantial 35 distance and engage the upper inclined face of said flange to hold the shank firmly against the under face of the rail, and a laterally extending arm at the opposite end of the shank adapted to be sprung into abutting engagement 40 with the edge of the rail in non-overhanging relation.

5. A rail anchor consisting of a shank adapted to extend across the rail base and provided at one end with three integral jaws 45 all adapted to extend over the rail base flange and engage the upper inclined face thereof to hold the shank firmly against the under face of the rail, one of the jaws being positioned above the shank and the other two jaws 50 being positioned at the opposite sides of and in spaced relation to said jaw, and means at the opposite end of the shank for gripping the rail base flange at the opposite side of the rail.

55 6. A one-piece rail anchor consisting of a shank adapted to extend across the rail base to abut against a tie and provided at one end with a jaw positioned above the shank and with a second jaw spaced laterally from the 60 first jaw in the direction of the on-coming traffic, each jaw being formed to extend inwardly from its connection with the shank over the rail base flange a substantial distance toward the central web of the rail to engage the upper inclined face of the rail.

base and hold the shank firmly against the under face of the rail, and an arm at the opposite end of the shank extending in the direction of the on-coming traffic and adapted to be sprung into abutting engagement with the edge of the rail in non-overlapping relation therewith.

7. A rail anchor consisting of a shank adapted to extend across the rail base and provided at one end with three laterally spaced jaws extending over the rail base flange to engage the upper inclined face of said flange and the jaws having their flange engaging faces normally offset slightly from the horizontal plane to cause them to exert a strong spring gripping action on the rail flange to hold the shank firmly against the under face of the rail base, and means at the opposite end of the shank for gripping the rail base flange at the opposite side of the rail.

8. A one-piece rail anchor consisting of a shank adapted to extend across the rail base to abut against a tie and provided at one end with a jaw positioned above the shank but off-set from the plane of the shank in the direction of the on-coming traffic and adapted to extend inwardly over the upper inclined face of the rail base flange to hold the shank firmly against the rail base, and an arm at the opposite end of the shank extending in the direction of the on-coming traffic and adapted to be sprung into abutting engagement with the edge of the base flange in non-overhanging relation.

9. A rail anchor consisting of a shank adapted to extend across the rail base and provided at one end with three jaws positioned to extend over the rail base flange and engage the upper inclined face thereof to hold the shank firmly against the rail base, said jaws consisting of a central jaw having one end portion bent toward the upright central rail web to form a second jaw and having its opposite end portion bent away from said upright web to form the third jaw, and means at the opposite end of the shank for gripping the rail base flange at the opposite side of the rail.

10. A rail anchor consisting of a shank adapted to extend across the rail base and provided at one end with three integral jaws positioned to extend over the rail base flange and engage the upper inclined face thereof to hold the shank firmly against the rail base, said jaws consisting of a central jaw and jaws spaced from the opposite sides thereof and connected to cause the central jaw to form the central portion of the letter S and the jaws spaced therefrom to form the end portions of the letter S, and means at the opposite end of the shank for gripping the rail base flange at the opposite side of the rail.

11. A rail anchor consisting of a shank

70

75

- adapted to extend across the rail base and provided at one end with three laterally spaced jaws positioned to extend over the rail base flange and consisting of an intermediate jaw having a second jaw connected to one end thereof and a third jaw connected to the opposite end thereof and the jaws having their flange engaging faces normally disposed slightly out of alignment to cause them to engage the upper inclined face of the base flange with a powerful spring action to hold the shank firmly against the under face of the rail base, and means at the opposite end of the shank for gripping the rail base flange.
12. A blank cut to form a one-piece rail anchor and consisting of a sheet of metal having approximately a rectangular configuration with one entire upper corner cut away lengthwise of the blank well toward the central portion of the blank, said blank being further cut away by a straight cut extending lengthwise of the central portion of the blank and under a substantial part of the remaining upper portion of the blank to form a rail engaging surface adapted to abut against the under face of the rail base, said remaining upper portion of the blank being further cut away at its opposite edges to form deep rail flange-receiving slots therein, and the opposite end of the blank being cut to form an arm adapted to rest against the rail edge in non-overhanging relation therewith.
13. A blank cut to form a one-piece rail anchor and consisting of a sheet of metal having approximately a rectangular configuration with one entire upper corner cut away lengthwise of the blank well toward the central portion of the blank, said blank being further cut away by a straight cut extending lengthwise of the central portion of the blank and under a substantial part of the remaining upper portion of the blank to form a rail engaging surface adapted to abut against the under face of the rail base, said remaining upper portion of the blank being further cut away along inclined lines above said straight cut to form a rail flange clearance space and a pair of overhanging flange-engaging jaws and having its outer edge cut away to form a third overhanging flange-engaging jaw, and the opposite end portion of the blank being cut to form a rail edge engaging abutment at the end of the blank.
14. A one-piece rail anchor comprising a shank extending across the rail base diagonally to the longitudinal axis of the rail and cooperating tie, three jaws at the end of the shank which is out of contact with the tie to extend over the rail base flange a substantial distance and engage the upper inclined surface of said flange with sufficient force to hold the shank against the under face of the rail base, a laterally curved arm at the end of the shank which bears against

the tie having its end in firm gripping engagement with the edge of the rail base at a point diagonal with relation to the said jaws so that the end of the arm will automatically increase the gripping action of the rail anchor on the rail base in a ratio substantially equivalent to the increase in the creepage load.

15. A rail anchor consisting of a shank adapted to extend across the rail base to abut against a tie and provided at one end with a plurality of laterally spaced overhanging jaws to extend inwardly a substantial distance over the rail base and to engage the upper inclined face thereof to hold the shank against the rail base and one of said jaws having a lower jaw member spaced laterally from the shank and adapted to engage the under surface of the rail base, and an arm extending laterally from the opposite end of the shank to bear against the rail edge in non-overlapping relation therewith.

16. A one-piece rail anchor consisting of a shank adapted to extend across the rail base to abut against a tie and provided at one end with a jaw positioned above the shank and with a second jaw spaced laterally from the first jaw in the direction of the on-coming traffic, a third jaw positioned below the second jaw and adapted to be forced upwardly against the lower face of the rail base with an increased pressure as the shank tends to rock about its upper longitudinal edges under the tie pressure, and means at the opposite end of the shank for engaging the base flange at the opposite side of the rail.

In testimony whereof, I have signed my name to this specification.

CHARLES G. ERICSON.
